COMBINED DOOR-HOLDING AND DOOR-CHECKING DEVICE

Rudolph I. Schonitzer, Shaker Heights, Ohio

Application August 11, 1934, Serial No. 739,426

Renewed December 10, 1937

15 Claims. (CL 16-86)

This invention relates to a device for releasably holding a hinged door in open position and for cushioning outward swinging movement thereof, the present device being of the same general character as that disclosed in my prior application for a Combined door-holding and door-checking device, application Serial No. 727,891, filed May 28, 1934, which eventuated in Patent No. 2,137,197, November 15, 1938.

10 The general object of the present invention is the provision of a door-holding and door-checking device which is of simple and inexpensive construction, of strong and sturdy character, and of great utility.

15 Further objects of the present invention are to provide for structural simplicity, compactness, manufacturing economy and certainty of operation under all predetermined conditions.

With the foregoing and other objects in view 20 which will appear as the description of the present invention proceeds, said invention resides in the combination and arrangement of parts and in the details of construction hereinafter described and claimed, it being understood that changes in 25 the present invention as herein disclosed can be made within the scope of what is claimed without departing from the spirit of the invention.

The invention will be readily understood from 30 the following description of one embodiment thereof, reference being had to the accompanying drawings in which

Fig. 1 is a side elevation of a portion of an automobile body, each of the four doors thereof (two of which are shown) having associated therewith a combined door-holding and door-checking device embodying the present invention; Fig. 2 is a horizontal, longitudinal sectional view of a portion of the left front door of said body and a portion of the post or pillar structure 35 thereof on which said door is hingedly mounted, the door being in closed position and the holding and checking device therefor being in inoperative position, the view being on the line 2-2, Fig. 1; Fig. 3 is a view similar to Fig. 2 but showing the 40 door releasably held in open position by said device; Fig. 4 is a vertical, longitudinal sectional view of the parts of Fig. 3, the view being on the line 4-4, Fig. 3; and Figs. 5, 6 and 7 are detail cross-sectional views on the lines 5-5, 45 6-6 and 7-7, Fig. 4, respectively.

In the portion of the automobile body shown 50 in Fig. 1, 1 represents the left front door and 2 the left rear door thereof, the front door 1 having its front side edge portion mounted by the usual hinges 3 on the front post or pillar 4 of said

body and the rear door 2 having its rear side edge portion mounted by the usual hinges 5 on the rear post or pillar 6 thereof.

To effectively prevent undesired closing movement of hinged doors, whether mounted on vertical or non-vertical axes, the device of the present application was designed, the chief function of which is to releasably and automatically hold a hinged door in open position whenever it is moved thereto. To avoid the necessity of using 10 a separate device for cushioning the opening movement of such a door, the present device is so constructed that it also functions as a check or cushioning means therefor, all as will herein-after more fully appear.

15 For purposes of illustration, the details of construction of the holding and checking device for the left front door 1 of the automobile body of Fig. 1 are shown in Figs. 2 to 7 inclusive of the accompanying drawings, it being understood 20 that the holding and checking devices for the other doors of said body are of like construction.

As shown, the present improved door-holding and door-checking device includes a relatively flat metal strap or link 10 having its rear end pivotally or otherwise suitably connected to the door 1, preferably to an intermediate portion of the hinged side thereof, such as between the hinges 3. Such connection of said strip or link to said door is here effected by the use of a bifurcated lug 12 welded or otherwise suitably secured to the front edge wall 13 of the door and by a rivet 14 or the like connecting the rear end of the strap or link to said lug.

The front or free end of said strap or link 10 35 lies within the space 16 in the left front body post or pillar structure, said structure comprising the left front body post or pillar 4 and outer and inner body side walls 18, 19 suitably secured thereto, the outer side wall 18 being of metal, as is usual, and the inner side wall 19 being of the usual pasteboard material.

The rear wall 21 and the front wall 22 of the body post or pillar 4 are respectively provided with suitable openings 23, 24 through which the strap or link 10 extends, and a suitable yieldable projecting means is suitably mounted on the front or free end portion of said strap or link within the aforesaid space 16, said projecting means being here shown as a generally cubical block of rubber 27 and being mounted on said strap or link front or free end portion between two spaced abutment means, the construction of which will be later described.

Arranged within the space 16 of the left front 55

post or pillar structure and welded or otherwise suitably secured to the front wall 22 of the post or pillar 4 thereof, over the strap or link-receiving opening 24 in said post or pillar wall 22, is a suitable rigid retaining means for releasably receiving and retaining, upon opening movement of the door 1, the resilient projecting means, the rubber block 27 in the present embodiment, of the strap or link 10, thereby enabling said door 10 to be automatically maintained in open position whenever it is moved thereto.

The retaining means here shown for the rubber block 27 is of generally box-like character, comprising a pair of opposed retaining side wall portions in the form of metal strips 31 and a pair of opposed connecting side wall portions in the form of metal strips 30, the latter having integrally formed therewith side flanges 32 which are welded or otherwise rigidly secured to side flanges 34 with which the retaining strips 31 are integrally provided. Such rigid inter-connection of said retaining and connecting strips results in the provision of a rigid box-like retaining means, into the chamber 40 of which the rubber block 27 of the strap or link 10 is adapted to be forcibly drawn and releasably retained upon opening movement of the door 1.

As best shown in Fig. 4, the two rigid retaining strips 31 of the aforesaid box-like retaining means, and those two opposed side walls 42 of the rubber block 27 which cooperate therewith, are of generally convex form for yieldable inter-engagement in effecting a releasable retention of the door 1 in open position whenever it is moved thereto. To permit lateral distortion of said rubber block when it is forcibly drawn into the chamber 40 of said retaining means, upon opening of the door 1, said chamber has a cross-sectional shape differing from the normal cross-sectional shape of said block. As here shown, the chamber 40 of said retaining means is of generally rectangular cross-sectional shape and the rubber block 27 is of generally square cross-sectional shape, with the result that said chamber permits elongating lateral distortion of said block within said chamber upon the forcible entry of said block into said chamber, as indicated in Fig. 7 and as will be readily understood.

To cushion lateral movement of the strap or link 10 in the openings 23, 24 of the body post or pillar 4, the opening 24 in the front wall 22 of said post or pillar has associated therewith a resilient disc 45 of rubber or the like, said disc being provided with a centrally disposed slot 46 to receive said strap or link, said disc slot being smaller than either one of the post or pillar openings 23, 24 and being located in registration with the post or pillar front opening 24. Such association of said disc with said post or pillar opening 24 is effected and maintained by the securing of the present retaining means to said post or pillar, the four side walls of said retaining means, namely, the two retaining strips 31 and the two connecting strips 30, being provided at their rear ends with suitable flanges 48 to provide a suitable confining seat for said disc, as clearly shown in Figs. 2, 3 and 4. In the illustrated embodiment of the present invention, the securing of the retaining means to the front wall 22 of the post or pillar 4 is effected by welding or otherwise rigidly securing to said wall laterally extending flanges 50 with which the retaining strips 31 are integrally provided at their rear ends, and such securing of said retaining means also effects and maintains the disc 45 in

proper association with the post or pillar opening 24.

To prevent endwise enlargement of the disc slot 46 by the movement therein of the strap or link 10, upon opening of the door 1, the connecting strips 30 of the present retaining means are given a tapered form, as shown in Figs. 2 and 3, the effect of which is to so guide the rubber block 27 of said strap or link into the chamber 40 of said retaining means that any substantial "sawing" of the disc 45 by movement of said strap or link in the slot 46 of said disc is effectively prevented.

Although the rubber block 27 may be mounted on the strap or link 10 by any suitable means and in any suitable manner, said block is here shown as mounted on said strap or link between two abutment means, the front one of which is fast on said strap or link and the rear one of which is slidably thereon, to a limited degree, in response to and in accordance with distortion of said rubber block.

The front abutment means for the block 27 is here shown as in the form of a cotter pin 55, secured in a suitable opening in the front or free end portion of the strap or link 10, and a suitable flat metal collar 56 mounted on said strap or link between said cotter pin and the front end of said rubber block. The rear abutment means for said block is here shown as in the form of two superposed flat metal collars 57, 58 provided with oppositely disposed integral tongues 59, 60 extending through and movable in a longitudinally disposed slot 61 with which the front or free end portion of the strap or link is provided internally or intermediate its side edges. The tongue of each of said collars may extend through a side edge thereof, as here shown, in which case said collars may be applied to the strap or link, and the tongues thereof extended through the strap or link slot 61, by lateral or sidewise movement of said collars. The rear collar 58 is provided with two forwardly extending, opposed side flanges 65, between which the cooperating front collar 57 is confined against escaping, lateral or sidewise movement, said confining flanges 65 being clearly shown in Figs. 5 and 6.

By such construction, a very satisfactory rear abutment means for the rubber block 27 is simply and inexpensively provided, the two collars 57, 58 constituting said abutment means being capable of convenient assembly with the strap or link 10 in a manner to permit limited movement of said collars in response to and in accordance with distortion of said block, yet without liability of accidental escape of said collars. Moreover and equally important, the use of notches or the like in the side edges of said strap or link, which would inevitably damage the resilient disc 45 during repeated movements of the door 1, is entirely avoided.

When the door 1 is in closed position, as in Figs. 1 and 2, substantially all of the strap or link 10 lies within the left front post or pillar structure, the intermediate portion of said strap or link extending centrally through the box-like retaining means and any lateral movement of said strap or link being effectively cushioned by the resilient disc 45. Upon opening movement of said door, approximately one-half of said strap or link is withdrawn from said post or pillar structure, as shown in Fig. 3, said strap or link moving clockwise with said door and the rubber block 27 of said strap or link being forcibly drawn into and being releasably retained in the cham-

ber 40 of said retaining means, as shown in Fig. 4.

In this way, the door 1 is releasably retained in open position whenever it is moved thereto, without, however, interfering with the normal closing of the door, whenever desired. Such automatic and releasable retention in open position of hinged automobile doors and the like is quite desirable, especially those doors which are mounted on non-vertical axes with a consequent tendency to swing to closed position.

After entering the chamber 40 of the present retaining means, upon opening movement of the door 1, the rubber block 27, through its movable rear abutment means, yieldingly strikes or engages the post or pillar-backed resilient disc 45 and thus effects a further cushioning of said door in the final part of its opening movement.

The present device, therefore, effectively accomplishes the dual function of releasably holding the door 1 in open position whenever it is moved thereto and of cushioning the final part of the outward or swinging movement thereof. As a result, the use of a separate check or cushioning means for said door is obviously unnecessary.

If desired, of course, use of the retaining means of the present device may be omitted or dispensed with and the strap or link 10, with its rubber block 27, used for door checking or door cushioning purposes only, all as will be readily understood. Other changes in the present device as herein illustrated and described may obviously be made within the scope of the appended claims.

What I claim is:

1. A device for releasably holding a door member in open position with respect to a frame member, said device comprising a link adapted to be secured to one of said members, chambered retaining means of rigid character adapted to be secured to the other of said members, and elastic means carried by said link and adapted for releasable retention in the chamber of said retaining means when said door member is opened, thereby enabling said door member to be releasably held in such open position, the chamber of said retaining means having one of its cross dimensions greater and another one less than the corresponding cross dimensions of said elastic means, whereby said elastic means is enabled to expand laterally in the chamber of said retaining means when the door member is opened.

2. A device for releasably holding a door member in open position with respect to a frame member, said device comprising a link adapted to be secured to one of said members, chambered retaining means of rigid character adapted to be secured to the other of said members, and resilient means carried by said link and adapted for releasable retention in the chamber of said retaining means when said door member is opened, thereby enabling said door member to be releasably held in such open position, the chamber of said retaining means having a generally rectangular cross-sectional shape and said resilient means having a generally square cross-sectional shape, with the result that said chamber permits lateral expansion or distortion of said resilient means in the chamber of said retaining means upon its retention therein.

3. A device for releasably holding a door member in open position with respect to a frame member, said device comprising a link adapted to be secured to one of said members, rigid retaining means adapted to be secured to the other of said

members, and resilient means carried by said link and adapted for releasable retention by said retaining means when said door member is opened, thereby enabling said door member to be releasably held in such open position, said retaining means including a pair of opposed retaining portions each having a generally convex part and a generally concave part and a pair of opposed connecting portions of generally straight tapered form, said connecting portions rigidly interconnecting said retaining portions at the sides thereof and thereby providing a generally box-like structure for the releasable reception of said resilient means.

4. A device for releasably holding a door member in open position with respect to a frame member, said device comprising a link adapted to be secured to one of said members, rigid retaining means adapted to be rigidly secured to the other of said members, and resilient means carried by said link and adapted for releasable retention by said retaining means when said door member is opened, thereby enabling said door member to be releasably held in such open position, said retaining means including a pair of opposed retaining portions and a pair of opposed guiding portions of tapered form, said retaining and guiding portions providing a generally box-like structure for the releasable reception of said resilient means.

5. A device for releasably holding a door member in open position with respect to a frame member, said device comprising a link adapted to be secured to one of said members, rigid retaining means adapted to be rigidly secured to the other of said members, and resilient means carried by said link and adapted for releasable retention by said retaining means when said door member is opened, thereby enabling said door member to be releasably held in such open position, said retaining means including a pair of opposed retaining portions and a pair of opposed guiding portions of tapered form, said guiding portions rigidly interconnecting said retaining portions at the sides thereof and thereby providing a generally box-like structure for the releasable reception of said resilient means.

6. A device for releasably holding a door member in open position with respect to a frame member, said device comprising a link adapted to be secured to one of said members, socket-form retaining means adapted to be enclosed by and secured to the other of said members, said last mentioned member having an opening through which said link extends, means mounted upon said link within said last mentioned member for releasable retention within the socket of said retaining means when said door member is opened, thereby enabling said door member to be releasably held in such open position, and resilient means associated with said opening for cushioning lateral movement of said link therein and preventing the link from making contact with the end walls of said opening, said resilient means constituting the bottom wall of the socket of said retaining means and being maintained in association with said opening by portions of said retaining means located outside of said socket.

7. A device for releasably holding a door member in open position with respect to a frame member, said device comprising a link adapted to be secured to one of said members, socket-form retaining means adapted to be enclosed by and secured to the other of said members, said last

5 mentioned member having an opening through
5 which said link extends, means mounted upon
said link within said last mentioned member for
retovable retention within the socket of said
retaining means when said door member is
10 opened, thereby enabling said door member to be
releasably held in such open position, and resilient
means associated with said opening for cushioning
lateral movement of said link therein and prevent-
15 ing the link from making contact with the edge
walls of said opening, said resilient means con-
stituting the bottom wall of the socket of said
retaining means and said retaining means being
provided at its bottom and outside the socket
thereof with a confining seat for said resilient
means so as to maintain said resilient means in
association with said opening.

20 8. In a device for controlling the movement of
a hinged door, a link having mounted thereon
20 a pair of spaced abutment means and a resilient
means therebetween, one of said abutment means
having limited slidable movement on said link by
means of a tongue with which said last men-
25 tioned abutment means is provided and by a
longitudinally disposed, tongue-receiving slot
with which said link is provided intermediate its
side edge portions.

25 9. In a device for controlling the movement of
a hinged door, a link having mounted thereon a
30 pair of spaced abutment means and a resilient
means therebetween, one of said abutment means
comprising a pair of superposed collar members
having limited slidable movement on said link
by means of oppositely disposed tongues with
35 which said collars are provided and by a longi-
tudinally disposed, tongue-receiving slot with
which said link is provided intermediate its side
edge portions.

40 10. In a device for controlling the movement of
a hinged door, a link having mounted thereon a
40 pair of spaced abutment means and a resilient
means therebetween, one of said abutment means
comprising a pair of superposed collar members
one of which is provided with side flanges be-
45 tween which the other is confined, said collar
members having limited slidable movement on
said link by means of oppositely disposed tongues
with which said collar members are provided and
by a longitudinally disposed tongue-receiving slot
50 with which said link is provided intermediate its
side edge portions.

55 11. A device for releasably holding a door mem-
ber in open position with respect to a frame mem-
ber on which such door member is hinged, said
device comprising a link adapted to be pivotally
secured to one of said members, resilient means
carried by said link within the other of said
members, and retaining means adapted to be rig-
idly secured to said last mentioned member and
60 having two spaced retaining portions of rigid
character for receiving and releasably retaining
therebetween, upon the opening of said door
member, the resilient means of said link, with a
consequent releasable holding of said door mem-
65 ber in such open position, the space between said
rigid retaining portions being less than the nor-
mal corresponding cross dimension of such re-
siliency means, so that displacement of at least
a part of said resilient means occurs along the
70 other cross dimension thereof.

12. A device for releasably holding or retaining
a door member in a predetermined open position
with respect to a frame member, said device com-
prising socket-form retaining means of rigid
character adapted to be secured to and enclosed
5 by one of said members, a link adapted to be
secured to the other of said members and to ex-
tend into said first-mentioned member and
through the socket of the retaining means se-
cured thereto, and resilient means mounted upon
said link within said first-mentioned member for
releasable retention by said retaining means
10 within the socket thereof when said door member
is in a predetermined open position, thereby en-
abling said door member to be releasably held or
retained in such open position, the longitudinal
axis of the socket of said retaining means being
15 angularly disposed relative to the corresponding
axis of that portion of the link which extends
through said socket when said door member is
in closed position relative to said frame member.

13. A device for releasably holding or retaining
a door member in a predetermined open position
with respect to a frame member, said device com-
prising retaining means adapted to be enclosed
20 by one of said members and secured to a portion
thereof which is angularly disposed relative to a
side wall portion of such member, a link adapted
to be secured to the other of said members and
25 to extend into said first-mentioned member and
through the retaining means secured to a portion
thereof, and means mounted upon said link for
cooperation with said retaining means in re-
leasably holding or retaining said door member
30 in a predetermined open position.

35 14. In a device for controlling the movement
of a door member hinged on a frame member,
a link associated with one of said members and
having a longitudinally extending slot and a lat-
40 eral shoulder spaced longitudinally from such
slot, an abutment means slidably mounted on
said link and having a portion extending through
the slot thereof, and a resilient means mounted
45 on said link between and in engagement with said
lateral shoulder and said abutment means, said
abutment means being normally maintained by
said resilient means at that end of said slot which
is farther from said lateral shoulder.

50 15. A device for releasably holding a door mem-
ber in open position with respect to a frame mem-
ber, said device comprising a cushioning element
associated with one of said members, a link at-
tached to the other member and extending
55 through openings in said first mentioned mem-
ber and said cushioning element, retaining means
associated with said first mentioned member and
having retaining portions which form a retaining
chamber, means associated with said retaining
60 portions for holding the cushioning element in
such a position that the opening therein is main-
tained in alignment with the opening in said
first mentioned member, and a resilient element
carried by said link and being releasably held in
65 the chamber of said retaining means by the re-
taining portions thereof when the door member
is opened and said retaining chamber having a
space for lateral expansion of said resilient ele-
ment when outward pressure is exerted on the
70 open door member.
